UNITED STATES PATENT OFFICE.

WILLIAM BRAIDWOOD, OF MOUNT VERNON, NEW YORK.

VENTILATOR FOR CARS, &c.

SPECIFICATION forming part of Letters Patent No. 470,540, dated March 8, 1892.

Application filed February 19, 1891. Serial No. 382,015. (No model.)

To all whom it may concern:

Be it known that I, WILLIAM BRAIDWOOD, a citizen of the United States, residing at Mount Vernon, in the county of Westchester and State of New York, have invented new and useful Improvements in Ventilators for Cars and other Conveyances, of which the following is a specification.

This invention relates to an improvement in ventilators for cars, omnibuses, and other conveyances; and the invention consists in the details of construction set forth in the following specification and claim, and illustrated in the accompanying drawings, in which—

15 Figure 1 is a vertical plan view of a car with my ventilator. Fig. 2 is a sectional side elevation along $x x$, Fig. 1. Fig. 3 is a section along $y y$, Fig. 1. Fig. 4 is a section along $z z$, Fig. 1. Fig. 5 is a section along $v v$, Fig. 1. 20 Fig. 6 is a section along $w w$, Fig. 1.

In the drawings, the letters A A indicate two longitudinal trunks or pipes located at the upper part of the car. Outlets B allow the foul air to pass from the interior of the 25 car into one or another of the trunks A. Over the outlet B in each trunk are located deflectors C. These deflectors are oppositely arranged—that is, the deflectors in one trunk are inclined in an opposite direction to the 30 deflectors in the other trunk—so that when the car goes in one direction the deflectors in one trunk come into action, while when the car goes in the opposite direction the deflectors in the other trunk come into action. The 35 outlet-passages may be provided with gauze or netting, as seen in Fig. 6. The inlet-ducts D are provided with swinging lids or covers E, so that by opening or closing a lid air can be admitted or shut off, as desired. Each 40 duct has its independent lid, so that the degree and locality of ventilation can be arranged as required. The number of ducts can be increased or diminished, as desired.

The inlet end H of each trunk is straight, 45 while its outlet end is curved, as seen in Fig. 1. This inlet end may be somewhat deflected downward to prevent rain or snow from entering the trunk. When the car goes in the direction of arrow 1, Fig. 1, air passes into 50 one of the trunks in the direction of arrow 2

and out of the trunk, as indicated by arrow 3, and in its passage over the deflectors in said trunk the air creates a partial vacuum near or at each outlet B, so as to draw air out of the interior of the car. By placing a duct D 55 in each berth of a sleeping-car each passenger can regulate the ventilation to suit personal requirements. As the deflectors C are fixed, no setting or adjustment is required. As the outlet of each duct D points upward, 60 the incoming air is thrown upward to avoid drafts onto the heads or feet of the passengers, and, as each lid E has simply to be swung up or down for opening or closing, each passenger, even if inexperienced, can regulate 65 ventilation as required. The ducts D lead from a longitudinal pipe or channel F at the lower part of the car, and into this pipe F the air enters from the outside through the passages G in the side of the car. The trunks A 70 have each a valve K, which can be closed when the trunk is not in use, and slides L, operated by a bar M and handle N, can be made to close the outlets B of that trunk A which is not in use. The trunk A which is in use 75 has its valve K and outlets B open, and when the car is reversed the latter trunk has its valve K and outlets B closed, and the trunk formerly closed is then opened or regulated 80 as required.

What I claim as new, and desire to secure by Letters Patent, is—

1. The combination, with a pair of longitudinal trunks A, each having orifices B, and an inclined immovable deflector C over each 85 orifice, the deflectors in one trunk being inclined in a direction the reverse of those in the other trunk, of the horizontally-movable slides L for governing the orifices of each trunk, a bar M, extending longitudinally along 90 each trunk and attached to the slides thereof, and a handle N for moving each bar to simultaneously adjust the slides attached to such bar, substantially as described.

2. The combination, with a car or other conveyance, of the horizontal air-pipe F, extending continuously in juxtaposition to the bottom of the car and having a series of air-inlet tubes G extending laterally through the car-wall and placing the horizontal pipe in com- 95 100

munication with the external atmosphere, and the series of upright air-ducts D, rising inside the car from the horizontal air-pipe, provided at their upper ends with upwardly swinging lids E and discharging the air perpendicularly in a plane parallel with the plane of the upright air-ducts, substantially as described.

In testimony whereof I have hereunto set my hand in the presence of two subscribing witnesses.

WILLIAM BRAIDWOOD.
